CLAIM

The ornamental design for a cap with holders for eyeglasses, as shown and described.

DESCRIPTION

FIG. 1 is a perspective view of the cap with holders for eyeglasses of this invention.

FIG. 2 is a left side elevational view of the cap with holders for eyeglasses shown in FIG. 1.

FIG. 3 is a rear elevational view of the cap with holders for eyeglasses shown in FIG. 1; and,

FIG. 4 is a right side elevational view of the cap with holders for eyeglasses shown in FIG. 1.

The broken lines depicting a visor at the front of the cap in FIGS. 1–4 illustrate environmental matter and form no part of the claimed design.

The evenly spaced broken lines extending from the base to the crown of the cap in FIGS. 1–4 illustrate stitching, and form a part of the claimed design.
